United States Patent

Des. 240,915
Patented Aug. 10, 1976

240,915

BUILDING MEMBER TO BE USED FOR MOLDINGS, COLUMNS, OR THE LIKE

Robert Franklin Green, Morrison, Colo., assignor to
Johns-Manville Corporation, Denver, Colo.

Filed Apr. 29, 1974, Ser. No. 465,226

Term of patent 14 years

Int. Cl. D25—01

U.S. Cl. D25—74

FIG. 1 is a perspective view of a building member to be used for moldings, columns, or the like showing my new design;

FIG. 2 is an enlarged fragmentary perspective view of FIG. 1; and

FIG. 3 is an enlarged fragmentary perspective view of a second embodiment of the design of FIG. 1.

I claim:

The ornamental design for a building member to be used for moldings, columns, or the like, as shown and described.
